UNITED STATES PATENT OFFICE.

ROBERT A. NAGLER, OF NEW YORK, N. Y.

DESIGN FOR A TIP-CAT.

SPECIFICATION forming part of Design No. 29,553, dated October 25, 1898.

Application filed October 1, 1898. Serial No. 692,437. Term of patent 7 years.

To all whom it may concern:

Be it known that I, ROBERT A. NAGLER, a citizen of the United States, residing at the city of New York, borough of Manhattan, in the county of New York and State of New York, have invented and produced a new and original Design for a Tip-Cat, of which the following is a specification.

Reference is to be had to the accompanying drawings, forming a part of this specification, in which—

Figure 1 is a plan view of a tip-cat, illustrating my design. Fig. 2 is a transverse section of the same on the line 2 2 in Fig. 1, and Fig. 3 is a longitudinal section of the same on the line 3 3 in Fig. 1.

The design consists of a body portion A, having parallel side edges connecting with

tapering end portions, as indicated at B, said taper being on all four sides. Depressions C appear in the top and bottom of the body portion A, as shown at C, and depressions also appear at opposite edges of the body portion A, as shown at C'.

The principal feature of my design consists in a body portion having parallel sides connecting with tapering end portions and the depressions in the top and bottom of the body portion.

I claim—

The design for a tip-cat, herein shown and described.

ROBERT A. NAGLER.
